UNITED STATES PATENT OFFICE.

RICHARD SETZER, OF VALLEY CITY, NORTH DAKOTA, ASSIGNOR OF ONE-HALF TO
EDWARD WYTENBACH, OF VALLEY CITY, NORTH DAKOTA.

SELF-SHOCKER.

1,150,070.

Specification of Letters Patent. Patented Aug. 17, 1915.

Application filed September 6, 1912. Serial No. 718,907.

To all whom it may concern:

Be it known that I, RICHARD SETZER, a citizen of the United States, residing at Valley City, in the county of Barnes and State 5 of North Dakota, have invented certain new and useful Improvements in Self-Shockers, of which the following is a specification.

My invention relates to improvements in self shockers for binders and consists in improved 10 features of construction and combination hereinafter particularly described and claimed.

In the accompanying drawings forming part of this specification, Figure 1 is a plan view of my improved self shocker; Fig. 2 is a plan view of the same and the delivery end of the associated binder; Fig. 3 is an elevation of the lever side of the shocker; Fig. 4 is an outer side elevation of the 15 shocker; Fig. 5 is an elevation of part of the supporting mechanism for the bundle holder; Fig. 6 is a detail of a portion of the part shown in Fig. 5; Fig. 7 is an elevation of the delivery end of the shocker; Fig. 8 is a detail view of a locking lever forming part 20 of the invention; Fig. 9 is a detail view of a tripping arm forming part of the invention; Fig. 10 is a detail view of a portion of bundle placing mechanism forming part of 25 the invention, and Fig. 11 is a sectional detail view illustrating a lock for the compressing member.

Referring to the drawings, A represents the delivery end of an ordinary binder. Section 30 cured across the delivery end of the binder as by suitable connecting framework 2 is my improved shocker. B represents the frame of the shocker centrally supporting a raised platform 3 which forms a continuation of the ordinary delivery chute of the binder. Having hinge support 4 at the front side of the platform 3 is a dumping platform 5 normally held raised by a spring 6 connected with the fixed platform 3. Having 35 hinge support 7 in the forward end of the frame B is a plurality of rearwardly extending bars 8 upon which rests a platform 9. The platform 9 has pivotal support 10 in the side bars of the frame. The bars 8 and platform 9 are normally held raised by a rod 11 extending transversely underneath the bars 8, said rod being carried by arms 12 having fulcrum support 13 upon the side bars of the frame. The lever arm 12 at the inner side of the frame is operatively connected

with links 14 with an actuating lever 15 adjacent the driver's seat 16.

The bundles are delivered from the binder to the platforms 3 and 5 with the heavier butt ends resting upon the hinged platform 5, so that the weight of the butt ends of the bundles will tilt the platform 5 and allow the bundles to drop to the platform 9. Having pivotal support 48 in brackets 49 is a curved bundle receiving yoke 17, the yoke 60 being centrally connected with the upwardly extending framework 18 by a cord 19. The ends of the yoke member have vertically adjustable support in slots 20 in the brackets 49, the brackets having horizontally adjustable support through the medium of slots 21 and connecting bolt with slides 22 slidably supported upon the rear ends of the bars 23. The bars 23 have pivotal support 24 at their inner ends on the side bars of the frame B. 70 The slides 22 carrying the brackets 49 are normally held drawn inwardly upon the bars 23 by springs 25. Supported at one end upon the corresponding pivot 48 is a forwardly extending yoke member 26, the member 26 at its opposite end being unsupported. The unsupported end of the member 26 has cable connection 27 with an actuating handle 28 arranged adjacent the driver's seat. By actuating the handle 28 the 75 free end of the member 26 is drawn rearwardly through the medium of the cable 27 to cause it to coöperate with the bundle receiving member and press the bundles into a shock as hereinafter more particularly pointed out.

To shove the bundles as they drop upon the platform rearwardly into the bundle receiving member I provide the slide 50 extending transversely of the frame above the 80 platform and slidably supported at its ends on the longitudinally extending rods 29 supported above the side bars of the frame. The slide 50 is reciprocated through the medium of the pivotally connected link 31 and lever 100 arm 32, the link 31 being connected at one end with the slide and the lever arm 32 at its rear end being secured to a transverse shaft 33 journaled in the upper ends of the standards 34 carried by the framework. The transverse shaft 33 is connected by links 35 with an actuating handle 36 supported adjacent the driver's seat. Longitudinally slideable upon the slide 50 is a bundle engaging device 37 normally held on the outer end of 105 310

the slide by a coil spring 38 connecting it with the adjacent end of the slide. In order to draw the bundle engaging device toward the opposite end of the slide I provide the 5 cable 39 connected with said device and running over idlers 40 to an actuating lever 41 supported adjacent the driver's seat.

To hold the dumping platform in raised position when the shock delivery platform 10 and bars are lowered, as hereinbefore pointed out, I provide a lever arm 42 having fulcrum support 43 upon the outer side of the frame. The lever arm below its fulcrum support has an offset end 44 extending underneath the bars 8 so as to be engaged by said bars as said bars are dropped to turn said lever arm on its fulcrum and carry its offset upper end 45 into engaging support with the bundle dumping platform as shown 15 in Figs. 4 and 8.

For the purpose of engaging the shock compressing yoke member 26, when the platform 9 and bars 8 are lowered, I provide the inwardly extending trip 46 slidably supported on a bar 47 extending upwardly from the outer side of the frame B. Thus when the bars 8 and the supporting framework for the shock holder are allowed to drop into lowered position the trip will 20 strike the member 26 and raise the same, the shock holder member 17 being at the same time upturned with respect to bracket 49 by reason of its cord connection 19 with the overhead framework member 26 being 25 upturned as described will stay upturned until pulled downward by means of the cable 27.

In operation, the bundles from the binder are delivered upon the platforms 3 and 5 40 with their heavier butt ends resting upon the platform 5 causing said platform to tilt by the weight of the bundles and allow the bundles to drop to the receiving platform 9. The receiving platform 9 and bars 45 8, it will be understood, will be normally held in raised position by the mechanism heretofore described. As the bundles drop to the platform 9 the slide will be drawn rearwardly through its actuating mechanism 50 to carry the bundles into the receiving yoke member 17. In order to evenly position the bundles within the receiving yoke member the bundle engaging device may be moved along the slide as heretofore pointed out to 55 move the bundle laterally upon the platform 9 and carry it to the desired position within the yoke member 17. When the desired number of bundles have been carried into the shock holder, compressing yoke 26 may 60 be lowered and the free end thereof may be drawn rearwardly as hereinbefore pointed out to form the shock. The shock being formed the bars 8 and platform 9 and the shock holder supporting bars 23 will be allowed to drop by the lowering of the trans-

verse rod 11 through its actuating mechanism. As the free ends of the bars 8 and the supporting side bars for the shock holder drop the shock holder will slide rearwardly upon the downwardly inclined supporting bars 23. As the free ends of the supporting bars for the shock holder drop and the shock holder slides rearwardly thereon, the receiving member 17 will be raised by the cord connection 19 with the overhead framework, allowing the shock to slide under said member 17 to the ground. While the shock is being delivered bundles will be prevented from dropping to the platform 9 by reason of the dumping platform 5 being held raised 80 by the lever arm 42 which lever arm will be held in supporting position by the engagement therewith of the lowered bars 8. 70

51 represents a catch carried by one of the brackets 49 to engage the member 26 when 85 raised to the full lines shown in Fig. 4 and to hold the same raised. To release the member 26 a cord 52 is connected with the member so that by pulling upon the same the member may be sprung in from the 90 catch. A jaw 53 on the end of the catch 51, as shown in Fig. 7, stands under the member 26 to hold the same in raised position. 95

I claim as my invention:

1. A self shocker comprising a framework, 95 a tilting bundle receiving platform carried by said framework, means for delivering bundles to said platform, a bundle receiving device having sliding hinge support above the delivery end of said platform, a bundle 100 transporting slide working upon longitudinal ways supported upon the frame above said platform and operable to carry bundles into the bundle receiving device, hand operated means for compressing bundles within 105 said device to form a shock, and means for tilting said platform when the shock is formed.

2. A self shocker comprising a framework, 110 a tilting platform supported by said framework, means for delivering bundles to said platform, means normally holding said platform raised, a bundle receiving device having sliding hinge support above the delivery end of said platform, a bundle 115 transporting slide working upon longitudinal ways supported upon the frame above said platform and operable to carry the bundles into said bundle receiving device, means for compressing bundles within said device to 120 form a shock, means for releasing said platform to allow it to tilt down when the shock is formed, and means for raising the bundle receiving device when said platform is so tilted to discharge said shock. 125

3. A self shocker comprising a framework, 130 a tilting bundle receiving platform carried by said framework, a dumping platform for delivering bundles to said bundle receiving platform, a bundle receiving device having

sliding hinge support above the delivery end of said bundle receiving platform, a bundle transporting slide working upon longitudinal ways supported upon the frame above said platform and operable to carry bundles into the bundle receiving device, hand operated means for compressing bundles within said device to form a shock, means for releasing said bundle receiving platform to allow it to tilt down when the shock is formed, and means for holding said dumping platform in operative position and raising said bundle receiving device out of the path of the contained shock when said bundle receiving platform is tilted down.

4. A self shocker comprising a framework, a tilting bundle receiving platform carried by said framework, a dumping platform for delivering bundles to said bundle receiving platform, a bundle receiving device having sliding hinge support above the delivery end of said bundle receiving platform, a

bundle transporting slide working upon longitudinal ways supported upon the frame above said bundle receiving platform and 25 operable to carry bundles into the bundle receiving device, hand operable means for compressing bundles within said device to form a shock, means for releasing said bundle receiving platform to allow it to tilt 30 down when the shock is formed, and means for holding said dumping platform in inoperative position and raising said bundle receiving device out of the path of the contained shock when the bundle receiving platform is lowered for the discharge of the shock.

In testimony whereof I affix my signature in presence of two witnesses.

RICHARD SETZER.
